UNITED STATES PATENT OFFICE.

HUBERT C. ELLIS AND NORMAN C. ELLIS, OF EVANSTON, ILLINOIS.

IRONING MACHINE.

Application filed March 20, 1926, Serial No. 96,113. Renewed September 6, 1928.

The invention relates to ironing machines and more particularly to that type in which a flat-iron is reciprocated by power over a fixed table under control of the operator.

- 5 One object of the invention is to provide a machine of this type with improved mechanism for reciprocating the flat-iron which comprises reverse gearing which is stationarily mounted on the frame.
- 10 Another object of the invention is to provide improved reciprocating mechanism in which the reverse gearing is stationarily mounted and controlled from a handle on the reciprocable flat-iron carriage.

- 15 Other objects of the invention will appear from the detailed description.
- The invention consists in the several novel features hereinafter set forth and more particularly defined by claims at the conclusion 20 hereof.

In the drawings: Fig. 1 is a perspective of a machine embodying the invention. Fig. 2 is a plan. Fig. 3 is a longitudinal section. Fig. 4 is a transverse section through the 25 flat-iron-carriage. Fig. 5 is a section on line 5-5 of Fig. 2. Fig. 6 is a diagram of the locking gears of the controller device. Fig. 7 is a detail of the carriage lifting device.

The invention is exemplified in a structure 30 comprising a supporting frame which is built up of sides 10, a longitudinal member 11 and a plate having a horizontal portion forming a base 13 and a vertical portion having a back, all of which are rigidly secured together in suitable manner, to form a rigid supporting structure. An ironing board or table is supported in an elevated position by a standard 16 adjacent one end, which is provided with an angular extension 17 to support the other end, so that garments may be slipped over the table. The ironing table is usually heated by any suitable means, usually electrically, in a manner well understood in the art. A flat-iron 18, containing a resistance element, is of sufficient weight to produce the necessary pressure for ironing, is reciprocable horizontally over the table 15 and is suspended by a uniform joint 19 from an arm 20, this joint permitting the necessary freedom of movement of the iron to cause it to engage the material being ironed. Arm 20 is formed on a carriage 24 which is provided with circular bearings 21 and 22 which are adapted to slide and rock on a shaft 23 which extends longitudinally across

the back of the frame and is fixed in the frame-sides 10.

The improved mechanism, for reciprocating the carriage, comprises a drive-shaft 25 which may be driven by a pulley 26 or from a motor in any suitable manner; a friction pulley 27 fixed to and constantly rotated by shaft 25; friction wheels 28 and 29 adapted to alternately contact with pulley 27, so as to be frictionally driven in opposite directions thereby; a transverse shaft 30 on which pulleys 28 and 29 are slidably mounted, and which is connected so as to be driven by said pulleys by a spline 39; a pulley 32 keyed to rotate with shaft 30; and an endless belt 33 driven by pulley 32 and extending longitudinally across the back of the frame and having its other end guided by an idler pulley 34 which is adjustably mounted, as at 35, so that any slack in the belt may be taken up when necessary. Shafts 25 and 30 are suitably journalled in a bracket 36 attached to one of the frame-sides 10. Belt 33 is connected to shift the carriage 24 by means of a lug 37 which is attached to the belt and extends into a groove 38 formed in the carriage 24, to permit the carriage to be rocked slightly to lift the iron off the work. Pulleys 28 and 29 are adapted to alternately engage the pulley 27 so the shaft 30 will be driven in opposite directions to operate the belt 33 in opposite directions, and are also adapted to assume a neutral position to stop the operation of the belt when desired.

In practice, it is desirable that reciprocation of the iron should be readily and conveniently controllable so the operator may start, stop and reverse the iron at any point within its range of movement. For this purpose, a controller handle 45 is mounted on the carriage 24 and is fixed to a shaft 46 which is pivotally confined in the arm 20 of the carriage. The connection for shifting the friction pulleys 28 and 29, which are carried by the frame, comprises a gear-wheel 47, fixed to rotate with shaft 46; a gear wheel 48, rotatable by gear 47, slidably and rotatably mounted on shaft 23, and shifted longitudinally with the carriage 24 by a fork 49 formed on the carriage and extending into an annular groove 50 in its hub; a fork 51 rigid with gear 48; a bail structure, which is adapted to be rocked by fork 51, and which comprises a longitudinal shaft 52 having its ends journalled in the frame-sides 10, arms 53 fixed

to said shaft and a longitudinal rod 54 fixed in said arms and extending through the fork 51, so that the shaft 52 may be rocked while the carriage is at any point within its range of movement; an arm 55 fixed to shaft 52 at the outer side of one of the frame-sides 10; a rod 56 reciprocable by said arm; and a shifter fork 57 pivoted to said rod, fulcrumed at 58, and provided with studs 59 extending into an annular groove 60 on the hub between pulleys 28 and 29. The teeth between gears 47 and 48 are of the interlocking type as shown in Fig. 6, so that gear 48 and the pulley shifting connection operable thereby will be locked in three positions to hold pulleys 28 and 29 in neutral position, in position to hold pulley 28 in frictional contact with drive pulley 27 or in position to hold pulley 29 in engagement with pulley 27. 20 This exemplifies a shifting connection for a reversible friction drive by which the driven pulleys will be locked in operative and neutral positions by the movement of the handle 45 on the carriage while the latter is 25 at any point within its range of travel.

In operation, assuming the handle 45 to be in neutral position, pulleys 28 and 29 will both be disengaged from pulley 27, at which time they will remain idle and the flat iron 30 carriage will remain stationary. When the handle 45 is rocked laterally in one direction, it will turn gear 47 which will turn gear 48 and fork 51 which travel with the carriage. The fork will shift rod 54 to rock shaft 52 which will rock the shifter fork 57 through arm 55 and rod 56 to bring the pulley 28 into engagement with the drive pulley 27, whereupon the carriage 24 and the flat iron carried thereby will be operated 40 in a rectilinear path in one direction. When the gear 48 has been thus shifted, it will be locked by gear 47 to hold the pulley 28 in frictional engagement with pulley 27. When the handle 45 is rocked in the opposite direction by the operator, gear 48 will be shifted 45 across its neutral position and into position to bring the pulley 29 into engagement with the drive pulley 27, whereupon the carriage and flat-iron will be operated longitudinally in reverse direction. In this position, the shifting connection will also be locked by the gear 47, so it will continue to be driven until the gear 47 is again shifted. This exemplifies a reversible friction drive gearing for reciprocating the carriage, which is stationarily 50 mounted on the frame, which may be readily locked in its several positions, and which is controllable by the manipulation of a handle on the carriage. To automatically stop the 55 carriage when it reaches the end of its stroke in either direction, an arm 59 is fixed to shaft 46, and abutments 60 and 61 are fixed to the frame-sides respectively. When the 60 carriage reaches the end of its stroke in one direction, abutment 60 will shift arm 59 to

bring the friction gearing into its neutral position, and when the carriage reaches the other end of its stroke, abutment 61 will shift arm 59 to bring the clutch shifting mechanism into neutral position. 70

In practice, it is frequently desirable to lift the iron over obstructions, such as buttons or thick seams, on the material being ironed, without stopping the iron, to facilitate work. To permit this to be done, provision is made 75 whereby the operator may manually and readily lift the iron off the work and lower it. Carriage 24 is free to rock on shaft 23 for this purpose. A roller 71 is mounted on the lower end of a loop 72, projecting downwardly from the carriage. This roller is adapted to be shifted by angle bar 73 which extends longitudinally across the back of the frame and is pivotally suspended at its ends by arms 70 which are hung to a shaft 52 which extends 80 between the frame-sides. Angle bar 73 carries a roller 74 which is adapted to be engaged 85 by a vertically sliding cam 75 on a rod 76 which is held in guides 77. A lever 78, for shifting the rod 76, is fulcrumed to the base at 90 79 and provided at its front end with a pedal 80, so that the operator may at any time, by depressing the pedal, swing the carriage 24 upwardly to lift the iron off the work and then permit it to drop. A spring 81 is applied 95 to normally hold cam 75 in its inoperative position. Roller 71 is normally disengaged by angle bar 73, so that the weight of the iron will be applied to the work. The range of movement of the flat-iron to the 100 right is sufficient to permit it to travel off the ironing table, and to effect automatic lifting of the iron and hold it supported after it passes off the table 15, a track 82 is formed adjacent one end of the angle bar 73 onto 105 which the roller 71 will ride before the iron leaves the table 15. The clearance between the drive pulley and the pulleys 28, 29 is sufficient so that the rocking of the carriage 110 sufficiently to lift the iron off the table, will not render either of the pulleys operable while handle 45 is in its neutral position. Springs 67 are interposed between arm 55 and collars 68 fixed to rod 56, to permit slight movement of arm 55 resulting from rocking of the carriage 24, without disengaging the pulleys 28 or 29 from the drive-pulley 27 by the vertical 115 rocking of the carriage 24. These springs also insure a driving engagement between the driven pulleys 28, 29 and the drive pulley 27. 120

The invention exemplifies an ironing machine in which the flat-iron may be reciprocated at the will of the operator by reverse gearing stationarily mounted on the frame; in which an endless belt for shifting the carriage is driven in opposite directions by said 125 gearing; in which the friction gearing is locked in operative position by a connection which is easily operable by a handle on the carriage; in which the flat-iron is adapted to 130

be lifted while the carriage is travelling; and in which provision is made for automatically unlocking and shifting the controlling device for the friction gearing.

5. The invention is not to be understood as restricted to the details set forth, since these may be modified within the scope of the appended claims, without departing from the spirit and scope of the invention.

10. Having thus described the invention, what we claim as new and desire to secure by Letters Patent, is:

1. In an ironing machine, the combination of a frame, an ironing table, a horizontally reciprocable carriage, a flat-iron mounted on the carriage and to reciprocate horizontally over the table, friction-gearing, mechanism for reciprocating the carriage driven by said gearing, and means mounted to travel with the carriage for controlling the gearing to start and stop the iron at will at any point within its range of travel.

2. In an ironing machine, the combination of a frame, an ironing table, a horizontally reciprocable and vertically swinging carriage, a flat-iron mounted on the carriage and to reciprocate horizontally over the table, friction-gearing stationarily mounted on the frame, mechanism for reciprocating the carriage driven by said gearing, means for controlling the gearing to start and stop the iron at will at any point within its range of travel, and means for swinging the carriage to shift the iron vertically.

3. In an ironing machine, the combination of a frame, an ironing table, a horizontally reciprocable carriage, a flat-iron mounted on the carriage and to reciprocate horizontally over the table, reversible gearing stationarily mounted on the frame, means operable by said gearing for reciprocating the carriage, and means mounted to travel with the carriage for controlling said gearing to start and stop the iron at will at any point within its range of travel.

4. In an ironing machine, the combination of a frame, an ironing table, a horizontally reciprocable carriage, a flat-iron mounted on the carriage and to reciprocate horizontally over the table, reversible gearing stationarily mounted on the frame, means operable by said gearing for reciprocating the carriage, and means, comprising a handle on the carriage connected to control said gearing to start and stop the iron at will at any point within its range of travel.

5. In an ironing machine, the combination of a frame, an ironing table, a horizontally reciprocable carriage, a flat-iron mounted on the carriage and to reciprocate horizontally over the table, reversible gearing stationarily mounted on the frame, mechanism operable by the gearing for reciprocating the carriage, and means comprising a handle travelling with the carriage, and a rock shaft operable

by said handle mounted in the frame and operable to control said gearing to start and stop the iron at will at any point within its range of travel.

6. In an ironing machine, the combination of a frame, an ironing table, a horizontally reciprocable carriage, a flat-iron mounted on the carriage and to reciprocate horizontally over the table, reversible gearing stationarily mounted on the frame, means operable by the gearing for reciprocating the carriage, a handle and gears operable thereby travelling with the carriage, a rock shaft mounted in the frame, means operable by the gears and comprising a sliding connection for rocking the shaft, to control said gearing to start and stop the iron at will at any point within its range of travel.

7. In an ironing machine, the combination of a frame, an ironing table, a horizontally reciprocable and vertically swinging carriage, a flat-iron mounted on the carriage and to reciprocate horizontally over the table, reversible gearing stationarily mounted on the frame, mechanism operable by the gearing for reciprocating the carriage, means comprising a handle travelling with the carriage and connected to control said gearing to start and stop the iron at will at any point within its range of travel, and means for swinging the carriage to lift the iron.

8. In an ironing machine, the combination of a frame, an ironing table, a horizontally reciprocable and vertically swinging carriage, a flat-iron mounted on the carriage and to reciprocate horizontally over the table, an endless belt connected to reciprocate the carriage, the reversible gearing for driving the belt in opposite directions, means to control the gearing to start and stop the iron at will at any point within its range of travel, and means to swing the carriage to lift the iron off the table.

9. In an ironing machine, the combination of a frame, an ironing table, a horizontally reciprocable and vertically swinging carriage, a flat-iron mounted on the carriage and to reciprocate horizontally over the table, reversible gearing comprising friction pulleys, means mounted to travel with the carriage for controlling the gearing to start and stop the iron at will at any point within its range of travel, spring-means for pressing the pulleys together, and means for swinging the carriage to lift the iron, said spring means operating to permit swinging of the carriage without affecting the position of the pulleys.

10. In an ironing machine, the combination of a frame, an ironing table, a horizontally reciprocable carriage, a flat iron mounted on the carriage and to reciprocate horizontally over the table, gearing comprising a drive-element and oppositely driven elements, mechanism operable by said driven

elements for reciprocating the carriage, means for shifting said elements to start and stop the iron at any point within its range comprising a pair of coacting gears, said gears embodying means to lock the driven elements in their assigned positions.

11. In an ironing machine, the combination of a frame, an ironing table, a horizontally reciprocable carriage, a flat iron mounted on the carriage and to reciprocate horizontally over the table, gearing comprising a drive-element and oppositely driven elements, mechanism operable by said driven elements for reciprocating the carriage, and means mounted to travel with the carriage for shifting said elements to start and stop the iron at will at any point within its range, said means embodying means to lock the driven elements in their assigned positions.
12. In an ironing machine, the combination of a frame, an ironing table, a horizontally reciprocable carriage, a flat iron mounted on the carriage and to reciprocate horizontally over the table, gearing comprising a drive-element and oppositely driven ele-

ments, mechanism operable by said driven elements for reciprocating the carriage, and a handle and gears travelling with the carriage and connected to shift said elements to start and stop the iron at will at any point within its range of travel, said gears embodying means to lock the driven elements in their assigned positions.

13. In an ironing machine, the combination of a frame, an ironing table, a horizontally reciprocable carriage, a flat iron mounted on the carriage and to reciprocate horizontally over the table, mechanism for reciprocating the carriage comprising reversible gearing, means mounted to travel with the carriage for controlling the gearing to start or stop the iron at will at any point within its range of travel, and means for automatically shifting the controlling means to stop the carriage when it reaches the ends of its stroke.

Signed at Chicago, Illinois, this 3rd day of March, 1926.
